UNITED STATES PATENT OFFICE

2,028,424

DOOR-CLOSING DEVICE

Albert van Dillen, Amsterdam, Netherlands

Application June 30, 1934, Serial No. 733,225

3 Claims. (Cl. 292—78)

The object of the present invention is to obtain a simple door-closing device for use on a double-swing door.

The device employed for this purpose according to the invention belongs to the type which remains inoperative except when the door is nearly closed, and the invention consists in the provision of a double-armed, forked lever which is mounted on the door frame in position to be swept by the free edge of the door, spring means being provided which tend to urge the lever into a central position except when it occupies a given position of obliquity in either direction, and a coupling member being fitted on the door which normally engages in known manner in the fork of the lever and which is adapted to leave and re-enter the fork after the lever has been turned by the door into either of its oblique positions.

Fig. 1 of the accompanying drawing represents a side view of a device constructed according to the invention.

Fig. 2 is a section on the line II—II of Fig. 1.

Fig. 3 is a sectional view like Fig. 2 of a modified construction, and

Fig. 4 is a sectional view of a still further modified construction.

In the constructions shown in Figs. 2 and 3 the device comprises a forked, double armed lever 4 which turns about a center on the door frame 1 and which is controlled by two springs 5 and 6. The latter act in opposite directions on the head of the lever and tend by their mutual action to maintain it in a central position. On a projecting stud 9, the door 2 carries a roller 10 which engages between the fork members of the lever and thus co-operates with the latter for maintaining the door closed. The door is adapted to open in either direction and will, when opened, turn the lever 4 into an oblique position, as shown by dotted lines in Figs. 2 and 3, whereupon, on further opening movement of the door, the roller 10 leaves the fork and frees the door from the closing device. The springs are so arranged that, when the lever has been turned by the door into the position in which the roller can leave the fork, the spring pressure is directed towards the center of the lever. The latter will therefore remain in this dead center position so that the roller 10, on the door being reclosed, can again enter into engagement with the closing device.

The door may be recessed for accommodating

the closing device, and the springs may be enclosed in a casing 3. In Fig. 2, the movement of the springs towards each other is limited by stops 7 and 8.

The arrangement shown in Fig. 3 differs from that of Fig. 2 in that the springs, instead of bearing direct against the head of the lever, act on the latter through the medium of pivoted arms 11 and 12 between which a stop 13 is arranged. By this arrangement the advantage is obtained that there is no need for the springs to occupy a definite position relative to the lever.

In the arrangement shown in Fig. 4, the door 2a only opens in one direction, and the spring 6 and arm 12 are therefore omitted. The closing lever 15 consists of a plain rod or bar 14, and the means for coupling the lever to the door consists of an inclined arm 17 which is secured to the door and fitted with two distanced rollers 15 and 16 between which the rod 14 engages when the door is closed.

The latter arrangement can advantageously be used on cupboard doors, chest lids and the like for causing them to snap into closed position, the catches ordinarily used for this purpose being omitted.

I claim:

1. A closing device of the character described for double-swing doors, comprising a double-armed, forked lever mounted on the door frame in position to be swept by the free edge of the door, spring means tending to urge the lever into a central position except when the lever occupies a given position of obliquity in either direction, and a coupling member on the door normally engaging in the fork of said lever and adapted to leave and re-enter the fork after the lever has been turned by the door into one of its oblique positions.

2. A structure as claimed in claim 1 wherein the spring means comprises two resilient arms which bear from opposite sides against the lever, and stops which limit the movement of the arms in inward direction.

3. A structure as claimed in claim 1 wherein the spring means comprises a pair of pivoted arms adapted to bear against the lever from opposite sides thereof, a spring tending to urge each arm against the lever, and a stop arranged between the arms for limiting the inward movement thereof.

ALBERT VAN DILLEN.
